(57) **CLAIM**

The ornamental design for a dog squeak toy, as shown and described.

DESCRIPTION

FIG. 1 is a front elevational view of a dog squeak toy, showing my new design;

FIG. 2 is a top plan view thereof;

FIG. 3 is a front and top perspective view thereof;

FIG. 4 is a bottom plan view thereof;

FIG. 5 is a rear elevational view thereof;

FIG. 6 is a left elevational view thereof; and,

FIG. 7 is a right elevational view thereof.

The broken lines in the drawings depict portions of the dog squeak toy that form no part of the claimed design.

1 Claim, 7 Drawing Sheets
